SEMIFROZEN JUICE DISPENSER OR SIMILAR ARTICLE

Robert B. Hartley, Columbia Heights, Minn., assignor to
The Cornelius Company, Anoka, Minn.

Filed Nov. 9, 1970, Ser. No. 25,901

Term of patent 14 years

Int. Cl. D15—08

U.S. Cl. D94—3

FIG. 1 is a front perspective view of a semifrozen juice dispenser showing my new design, the oposite side being a mirror image of the side shown; and

FIG. 2 is a front elevational view thereof.

The rear is plain and unornamented.

I claim:

The ornamental design for a semifrozen juice dispenser or similar article, substantially as shown and described.
